CLAIM

The ornamental design for a lock box, as shown and described.

DESCRIPTION

FIG. 1 is a front elevational view of the lock box, shown with the access door in the closed position;

FIG. 2 is a rear elevational view thereof;

FIG. 3 is a right side elevational view thereof, the left side elevational view being a mirror image thereof;

FIG. 4 is a top plan view thereof;

FIG. 5 is a bottom plan view thereof; and,

FIG. 6 is an upper perspective view thereof.

The portions of the lock box shown in broken lines are for illustrative purpose only and form no part of the claimed design.

1 Claim, 3 Drawing Sheets
